US00D828322S

(12) **United States Design Patent** (10) Patent No.: **US D828,322 S**
Ryu et al. (45) Date of Patent: ** Sep. 11, 2018

(54) **CELLULAR PHONE**

- (71) Applicant: **LG ELECTRONICS INC.**, Seoul (KR)
- (72) Inventors: **Seunghoon Ryu**, Seoul (KR); **Jeeyoung Yeon**, Seoul (KR)
- (73) Assignee: **LG ELECTRONICS INC.**, Seoul (KR)
- (**) Term: **15 Years**
- (21) Appl. No.: **35/502,307**
- (22) Filed: **Jul. 19, 2016**

(80) **Hague Agreement Data**

- Int. Filing Date: **Jul. 19, 2016**
Int. Reg. No.: **DM/092016**
Int. Reg. Date: **Jul. 19, 2016**
Int. Reg. Pub. Date: **Jan. 20, 2017**

(30) **Foreign Application Priority Data**

- Jan. 22, 2016 (KR) 30-2016-0003388
